[57] CLAIM

The ornamental design for an illuminated sculpture, as shown and described.

DESCRIPTION

FIG. 1 is a front isometric view of an illuminated sculpture showing my new design;

FIG. 2 is a top plan view thereof on an enlarged scale; FIG. 3 is a bottom plan view thereof on an enlarged scale;

FIG. 4 is a front elevational view thereof, the rear elevational view being identical; and,

FIG. 5 is a left side elevational view thereof, the right side elevational view being identical.

The stippled surfaces of the design are translucent.

FIG. 1.

FIG. 2.

FIG. 3.

FIG. 4.

FIG. 5.
